UNITED STATES PATENT OFFICE.

WILLIAM ILE, OF LYNBROOK, NEW YORK, ASSIGNOR TO HEMCO ELECTRIC MANUFACTURING COMPANY, INC., OF NEW YORK, N. Y., A CORPORATION OF NEW YORK.

ELECTRIC FUSE PLUG.

Application filed May 21, 1919. Serial No. 298,820.

To all whom it may concern:

Be it known that I, WILLIAM ILE, a subject of the King of Great Britain, residing at Lynbrook, in the county of Nassau and State of New York, have invented a new and useful Improved Electric Fuse Plug, of which the following is a specification.

This invention relates to fuse plugs for electric circuits. In the usual construction 10 of plugs of this character a threaded shell contact is provided to co-operate with a similarly arranged terminal contact in the cut out of an electric circuit, and a contact arranged centrally at one end of said shell contact to co-operate with another terminal contact of the cut out in the electric circuit, said contacts being carried and insulated from each other by a base of insulating material and electrically connected by a fusible 20 element usually carried within the base of insulating material, said base being hollow and open at the end opposite to the end contact, which opening is closed by a transparent closure to confine any flame or fire 25 which may be created upon the fusing of the fusible element, and also to ascertain whether or not the fusible member has been fused without removal of the plug from the cut out, and it is the object of the invention 30 to improve and simplify the general construction of plugs of this character and to provide a plug which is cheap and novel in construction and highly efficient in use.

In the drawing accompanying and forming 35 a part of this specification, Figure 1 is a sectional side elevation of a fuse plug showing an embodiment of my invention.

Figure 2 is a view of the annular member to secure the transparent closure to the 40 open end of the plug and looking at the top as viewed from Figure 1.

Figure 3 is a plan view of a member to be clamped between the transparent closure and the plug which may contain indications 45 as to the voltage and amperage of the electric current for which the plug is adapted.

Figure 4 is a plan view of the transparent closure; and

Figures 5 and 6 are end and side elevations, respectively, of a cylindrical member to engage within the plug.

Similar characters of reference designate like parts throughout the different views of the drawing.

55 The embodiment of the invention shown

in the drawing comprises a metallic annular threaded shell 7 to constitute one of the terminal contacts of the plug and adapted to engage a similarly formed terminal contact in the cut-out of an electric circuit to retain the plug in position therein. One end of the shell is embedded in an insulating material 9, such as "bakelite," which is molded in a plastic state to form a closure for said end of the shell.

A fusible element, such as a wire or rod 10 of lead or other suitable material, is located within the shell with one end of the wire engaging in and protruding through an opening in the insulating material axially of 70 the shell and in an opening in a metallic disk 8 embedded at the peripheral portions in the insulating material, and the protruding end of the wire fused and spread on the outer surface of the disk to secure the wire 75 to the disk and constituting the other terminal contact of the plug, as shown at 11. The other end of the fusible wire is soldered to the inner surface of the shell 7 adjacent the end opposite to the insulating material 9, as at 12.

To confine any flame or fire which may be created upon the fusing of the fusible wire 10, and also to view the interior of the plug from the exterior to ascertain whether or 85 not said fuse wire has been fused without removal of the plug from the cut out in the electric circuit, the end of the shell 7 opposite to the insulating closure 9 has a transparent closure in the form of a disk 13 of 90 insulating material, Figure 4. This transparent closure is held in place by a flanged annular member or ring 14 of insulating material (Figure 2). The ring 14 has an internal threaded portion 15 to correspond 95 with the threads of the shell 7 and the flange is adapted to engage the end of the shell to clamp the transparent closure between the end of the shell and said flange, as shown at 16. This insulating ring 14 also serves as 100 the means to place the plug in position and remove it from the cut out in the electric circuit.

To prevent the ring from unscrewing from the shell while placing the same in and removing it from the cut out it has recessed portions 17 for the reception of means, such as solder, when the ring is applied to the shell, as shown at 18, Figure 1, to fasten the ring and shell together.

A circular member 19 (Figure 3) having 110

an opening 20 may be clamped between the end of the shell 7 and the transparent closure, and which may have descriptive matter thereon indicative of the voltage and 5 amperage of the electric current with which the plug is adapted to be used.

The shell may also be provided with a lining of insulating material in the form of a sleeve 21 (Figures 5 and 6), which is adapted to be slipped into the shell from the end and is arranged with a slot 22 for the passage of the fusible wire 10 with a portion 23 extending at right angles to permit rotating the sleeve to lock the same in the shell 10 by the fuse wire. This sleeve is preferably of a material light in color to brighten up the interior of the shell whereby the interior may be readily observed through the transparent closure 13. This sleeve also prevents 15 the creating of an arc or the establishing of a circuit upon the fusing of the fusible wire.

Variations may be resorted to within the scope of the invention, and portions of the invention may be used without others.

25 Having thus described my invention, I claim:

1. In a fuse plug, a threaded metallic shell contact, an end contact, an insulating closure for one end of the shell molded in embedded relation to and insulating the shell and end contacts from each other and having a central perforation, a fuse wire within the shell in electrical connection with the shell and the end contact through the perforation in the insulating material, a transparent disk of insulating material to close the end of the shell opposite to the end contact, and an annular member having threaded connection with the end of the shell for 30 clamping the transparent closure disk and arranged to serve as a fingerpiece to manipulate the plug.

2. In a fuse plug, a threaded metallic shell to constitute a terminal contact of the plug, a closure for one end of the shell consisting of insulated material molded in embedding relation to one end of the shell and arranged with a central perforation, a fusible element within the shell electrically connected at one end with the interior of the shell and the opposite end of said element secured in the perforation in the molded closure to constitute an end terminal contact of the plug, a transparent disk closure for the open end of the shell, an annular member arranged for threaded connection with the shell and having an annular flange arranged to engage at the end of the shell and clamp the transparent closure between said flange and the end of the shell, 45 and a perforate member juxtaposed to the transparent disk arranged with descriptive matter for the purpose specified.

3. A fuse plug comprising a threaded shell contact; insulating material at one end of the shell molded in embedding relation thereto and serving to close said end of the shell and having a restricted opening therethrough axially of the shell; a fusible wire within the shell with one end in electrical connection with the shell and the other end extending through the opening in the insulating material with a portion thereof flattened exterior of said material to constitute the other terminal contact of the 50 plug; a sleeve of insulating material arranged to be slipped into the open end of the shell; a disk of transparent material to engage the end of the shell opposite to the insulating material; and an annular flanged member arranged to be threaded onto the shell and clamp the disk to the end of the shell.

WILLIAM ILE.
